ABSTRACT

A material handling device on a sewing machine for feeding labels one at a time to a movable vacuum pickup head on the machine which moves the label to

a position on the sewing machine adjacent the needle for sewing of the label onto a garment. The labels are cut from a strip wound on a reel. A reciprocable finger moves a portion of the strip along a surface and thereby unwinds the strip from the reel. On each label-feeding stroke of the finger, the strip is advanced a distance equal to the length or width of a label past a cutter and downwardly onto an elevator platform. The upper surface of the platform has at least one aperture therein which is connected to a vacuum source. The label is in a position on the platform covering the aperture and is held in position on the platform by vacuum from the vacuum source. With the label positioned and held on the platform, the cutter is actuated to cut the label from the remainder of the strip. While the cutter is cutting the label from the remainder of the strip, the elevator platform is simultaneously elevating the label to a position above the surface for subsequent pickup by the movable vacuum pickup head on the machine. As the pickup head moves into position to pick up the label, the vacuum is disconnected from the aperture in the platform so as to release its hold on the label and is connected to the pickup head. The pickup head by vacuum picks up the label and moves it from its position on the elevator platform to a position adjacent the needle for sewing of the label onto a garment. The elevator platform and cutter are lowered to their initial position. The finger then advances the strip a distance equal to the length or width of a label past the cutter and onto the platform. When the machine operator desires another label, the label is cut from the remainder of the strip, elevated, picked up, and positioned adjacent the needle and thereafter the next label is advanced past the cutter and onto the platform.

FIG. 1

FIG. 6

FIG. 8

FIG. 9

MATERIAL HANDLING DEVICE FOR FEEDING LABELS TO A SEWING MACHINE

BACKGROUND OF THE INVENTION

This invention relates to improvements in prior art machines for sewing labels on garments and, in particular, to material handling devices for feeding labels one at a time to a movable vacuum pickup head on the machine which moves the label to a position on the sewing machine adjacent the needle for sewing of the label onto a garment; of which U.S. Pat. No. 3,377,972 to Cohen et al is one example of such prior art machines.

In the label sewer described in U.S. Pat. No. 3,377,972, a plurality of cut labels are stacked vertically and placed in a magazine. The labels are picked up one at a time from the top of the stack by the movable vacuum pickup head of the sewing machine and moved to a position adjacent the needle for sewing of the label onto a garment. However, because the labels are made of a woven fabric and are therefore porous, it is difficult to consistently pick up just one label at a time from the stack by vacuum. In fact two, three, and as many as twelve labels may be picked up at one time from the stack by the vacuum pickup head and subsequently sewn onto a garment. As a result scrap losses increase because many labels and garments to which they are attached are wasted and, more manual handling of the labels and garments is required, all of which unnecessarily increases the unit cost of the garment.

SUMMARY OF THE INVENTION

This invention overcomes the deficiency of the prior art devices in a material handling device on a sewing machine by consistently feeding labels one at a time to a position on the sewing machine adjacent the needle for sewing of the label onto a garment.

The sewing machine includes a movable vacuum pickup head which picks up the labels one at a time from an elevator platform and moves a label to a position on the sewing machine adjacent the needle for sewing of the label onto a garment. The labels are cut from a strip wound on a reel. The strip may have transverse slits cut along the length thereof which are equally spaced apart a distance equal to the desired length or width of the labels. The transverse slits may be cut generally near the longitudinal centerline of the strip and do not extend to either of the longitudinal edges of the strip. A reciprocable finger moves a portion of the strip along a surface and thereby unwinds the strip from the reel. The finger is driven by a piston in a cylinder and has a tip which extends downwardly and in a label-feeding direction. The surface has a longitudinally extending groove and a portion of the tip of the finger extends downwardly into the groove. A portion of the strip unwound from the reel is positioned on the surface with the longitudinal centerline of the strip portion being substantially directly above and parallel to the longitudinal centerline of the bottom of the groove. On each label-feeding stroke of the finger, a portion of the tip of the finger engages one of the slits and advances the strip a distance equal to the length or width of a label past a cutter and downwardly onto an elevator platform. The upper surface of the platform has at least one aperture therein which is connected to a vacuum source. The label is in a position on the platform covering the aperture and is held in position on the platform by vacuum from the vacuum source.

When the machine operator desires a label, the cutter is actuated and the label which is positioned and held on the platform is cut from the remainder of the strip. While the cutter is cutting the label from the remainder of the strip, the elevator platform is simultaneously elevating the label to a position above the surface for subsequent pickup by the movable vacuum pickup head on the machine. As the pickup head moves into position to pick up the label, the vacuum is disconnected from the aperture in the platform so as to release its hold on the label. The vacuum disconnected from the aperture in the platform is connected to the pickup head. The pickup by vacuum picks up the label and moves in from its position on the elevator platform to a position adjacent the needle for sewing of the label onto a garment. The elevator platform and cutter are then lowered to their initial position. The finger then advances the strip a distance equal to the length or width of a label past the cutter and onto the platform. When the machine operator desires another label, the label is cut from the remainder of the strip, elevated, picked up by the movable vacuum pickup head and positioned adjacent the needle, and thereafter the next label is advanced past the cutter and onto the platform.

OBJECTS OF THE INVENTION

A primary object of this invention is to provide an improved material handling device on a sewing machine which will consistently feed labels one at a time to a movable vacuum pickup head on the sewing machine which moves the label to a position on the sewing machine adjacent the needle for sewing of the label onto a garment.

A further object of this invention is to provide an improvement which will decrease scrap losses by wasting fewer labels and garments to which they are subsequently attached, and thereby avoid unnecessarily increasing the unit cost of the garment.

These and other objects of the invention will become apparent after a consideration of the following detailed description taken in conjunction with the accompanying drawings wherein like reference characters designate like parts throughout the several views.

BRIEF DESCRIPTION OF THE FIGURES

FIG. 1 is a top plan view of the sewing machine, including the pickup head and material handling device, with the fingercarrying piston rod and cylinder removed for purposes of clarity;

FIG. 2 is a side elevation of the sewing machine, including the pickup head and material handling device, with the finger-carrying piston rod and cylinder shown;

FIG. 3 is a sectional view along line 3—3 of FIG. 1; as:

FIG. 4 is a perspective view of the material handling device;

FIG. 5 is a sectional view along line 5—5 of FIG. 1;

FIG. 6 is a sectional view along line 6—6 of FIG. 1 and showing the elevator platform in its initial lowered position;

FIG. 7 is a view taken along line 7—7 of FIG. 9 and is similar to FIG. 6 but shows the elevator platform in its elevated position;

FIG. 8 is a sectional view along the line 8—8 of FIG. 1 and showing the elevator platform in its initial lowered position;

FIG. 9 is a view taken along line 9—9 of FIG. 7 and is similar to FIG. 8 but shows the elevator in its elevated

position; and

FIG. 10 is a schematic representation of the pneumatic circuit for controlling the various components of the invention.

DETAILED DESCRIPTION OF THE PREFERRED EMBODIMENT

Referring to FIGS. 1 and 2, a sewing machine is shown having a conventional sewing head 1 and reciprocable needle bar 2 carrying a sewing needle 3 in the usual manner. Disposed beneath the forward end of the sewing head 1 is a movable vacuum pickup head 4 which is pivotable about a vertically extending shaft 5. The pickup head 4 has at least one aperture 4a therein which is connected to a vacuum source through a line 4b. The pickup head 4 has an arm 6 extending transversely therefrom which is connected through a pivot pin 7 to a cam actuated linkage 8. The linkage 8 is driven by a cam 9 mounted on a cam shaft 10. The cam shaft 10 is rotatably driven through appropriate clutching by a motor.

As shown in FIG. 3, the cam actuated linkage 8 includes a rocker arm 11 swingably supported by an axle 12 which is supported by a pair of axially spaced brackets 13. The rocker arm 11 includes a cam follower portion 11a. The axle 12 is rearwardly of, below, and parallel to the cam shaft 10. The cam actuated linkage 8 also includes an angulated connector rod 14 which is pivotally connected to the rocker arm 11 by a pivot pin 15. As shown in FIG. 3, cam 9 includes a raised section 9a and a depressed section 9b. When the section 9a engages the cam follower portion 11a, the vacuum pickup head 4 swings outwardly from the sewing head 1 to a position above a work station or elevator platform 26 of the material handling device to be subsequently described. When the section 9b engages cam follower portion 11a, the vacuum pickup head 4 swings inwardly toward the sewing head 1 to a position adjacent the needle for sewing a label, picked up by the pickup head from the elevator platform, onto a garment. The above movement is effected as follows: the respective cam section 9a or 9b of cam 9 pivots the rocker arm 11 about axle 12 which through pivot pin 15 moves connector rod 14 rearwardly or forwardly respectively to swing, through pivot pin 7, arm 6 and pickup head 4 about shaft 5 outwardly or inwardly respectively.

Also a mechanism is provided on the sewing machine to effect a lowering and raising of the vacuum pickup head 4 when it is in its outward position above the work station or elevator platform 26 to assist in picking up a label therefrom. This mechanism is likewise actuated by a cam on the cam shaft 10. Each of the above movements and mechanisms for effecting them are similar to those described in the aforesaid U.S. Pat. No. 3,377,972 whose disclosure is incorporated by reference herein.

The material handling device is shown most clearly in FIG. 4. The labels L to be fed to the sewing head 1 are wound in strip form on a reel 16 freely rotatably supported by a pair of upstanding brackets 17 mounted on a table 18. The strip S of labels may have transverse slits 19 cut therein. The slits 19 are equally spaced apart a distance equal to the desired length or width of a label L so as to define a label L between each adjacent pair of slits 19. The slits 19, if provided, may be cut generally near the longitudinal centerline of the strip and terminate inwardly of each of the longitudinal edges of the strip S.

A reciprocable finger 20 moves a portion of the strip S along a surface of the table 18 and thereby progressively unwinds the strip S from the reel 16. The finger 20 is driven by the piston rod 21 of an air actuated piston in a cylinder 22. Finger 20 has a tip 20a which extends downwardly and in a forward label-feeding direction.

The surface of the table 18 has a longitudinally extending groove 23 cut therein. A portion of the tip 20a of the finger 20 extends downwardly into the groove as shown in FIG. 5. The length of the groove is therefore substantially coincident with but preferably longer than the stroke of the finger 20.

A pair of longitudinally extending guide elements 24 are mounted on the surface of table 18. The guide elements 24 are transversely spaced apart a distance substantially equal to but slightly larger than the width of the strip S of labels L. The guide elements 24 are symmetrically disposed relative to the longitudinal centerline of the groove 23 so that the groove 23 is positioned centrally therebetween.

The reciprocable finger 20 may move a portion of the strip S along the surface of the table 18 by exerting a downward and forward pressure on the surface through the strip S. However, in this preferred embodiment, the stroke of the finger 20 is made slightly longer than the length or width of a label L (i.e., the spacing of the slits 19 if they are provided) so that on a rearward stroke of piston 21 and finger 20 the tip 20a passes over one of the slits 19. Thereafter, during the forward, label-feeding stroke, the portion of the tip 20a in groove 23, which is urging a small length of the strip S along the longitudinal centerline thereof downwardly, engages the slit which it had passed on the rearward stroke and moves the strip S forwardly a distance substantially equal to the length or width of a label L.

On each forward, label-feeding stroke of the finger 20, the strip is advanced a distance equal to the length or width of a label past a cutter 25 and downwardly onto the work station or elevator platform 26.

The cutter 25 comprises a stationary blade 25a and a movable blade 25b between which the strip is fed.

The stationary blade 25a is a metal bar which is secured at one end 27 to the surface of the table 18 by nuts 28. The other end 29 of the bar is not secured to the table. The bar extends transverse to the label-feeding direction. The forward transverse edge 30 of the bar cooperates with the movable blade 25b for cutting the label from the remainder of the strip S after the label has passed therebetween.

As shown in FIG. 6, the portion 31 of the bottom of the stationary blade 25a extending from the middle thereof to the end 30 is bevelled. Immediately below this portion of the bottom of the bar is a recess cut in the surface of the table 18. As shown in FIG. 6, the labels being fed to the elevator block 26 contact the bevelled portion 31 and are directed downwardly to the elevator block 26. The recess and the bevelled portion 31 provide a large passageway so that the forward edge of a label which is downwardly directed by the bevelled portion 31 will not contact portions of the surface of the table 18, thereby avoiding the possibility of the label's buckling up and not being fed to the elevator block 26. Likewise, as shown in FIG. 6, the rear edge of the bevelled portion 31 is a sufficient distance above the surface of table 18 so as to avoid any direct obstructing contact with the strip and thereby prevents the buckling up of any of the labels or the strip.

The movable blade 25b and the elevator block 26 lie within a generally rectangular opening 33 cut in the surface of table 18.

The upper surface 34 of the movable blade 25b is upwardly and rearwardly bevelled (FIG. 7) to provide a cutting edge 35 along the upper rear edge thereof. The edge 35 cooperates with the forward transverse edge of stationary cutter 25a for cutting the labels from the strip. The movable blade 25b is secured to the rear edge of one arm 36a of a bell crank 36. The bell crank 36 is pivotable about a pivot pin 37 secured to a bracket 38 which depends from the table 18. A spring 37a surrounds pivot pin 37 between a portion of the bracket 38 and the bell crank 36. Spring 37a thereby biases, through the bell crank 36, the movable blade 25b in a direction toward the stationary blade 25a for good shearing relation therewith. The other arm 36b of the bell crank 36 has its face end connected through a pivot pin 39 to the end of a piston rod 40. The piston rod 40 is reciprocable by means of an air actuated piston in a cylinder 41 secured to the bracket 38. Movement of piston rod 40 into cylinder 41 pivots the bell crank 36 clockwise about pivot pin 37 and moves the movable blade 25b upwardly past stationary blade 25a for cutting. Likewise, movement of piston rod 40 out of cylinder 41 pivots the bell crank 36 counterclockwise about pivot pin 37 and moves the movable blade 25b downwardly from the stationary blade 25a to its initial position.

The work station or elevator block 26 sets on and is supported by the upper surface of the arm 36a. One portion 43 of the bottom 42 of the elevator block 26 is generally level and the other portion 44 is bevelled. An edge 45 separates portion 43 from portion 44. As shown in FIG. 8, the bevelled portion 44 rests on the upper edge of arm 36a in the initial lowered position. As the bell crank 36 pivots clockwise about pivot pin 37 the upper edge of the arm 36a has the edge 45 in contact therewith and the arm 36a moves the elevator block 26 upwardly. As shown in FIG. 9, in the full elevated position the portion 43 rests on the upper edge of arm 36a. Also as the bell crank 36 pivots counterclockwise about pivot pin 37 the arm 36a and elevator block 26 thereon move downwardly to the initial position.

As shown in FIG. 8, a pair of posts 46, 47 extend downwardly from the bottom 42 of the elevator block 26. The posts ride in holes 48, 49 cut in the horizontal leg 50 of a bracket 38 which is secured to table 18. A spring 51 is placed over the bottom end of the post 46 which extends from the horizontal leg 50 of the bracket 38. A cap 52 is secured to the end of the post 46 and thereby compresses spring 51 between itself and the bottom of leg 50 for urging the elevator block 26 downwardly against the upper edge of the arm 36a. The holes 48, 49 guide the posts 46, 47 and thereby the elevator block 26 so that the elevator block 26 moves only vertically and not horizontally.

The upper surface of the elevator block is substantially level and has at least one aperture 26a therein. The aperture 26a is connected by a line 26b to the source of vacuum V. Appropriate valving to be subsequently described switches the vacuum from vacuum source V between the aperture 26b in the elevator block 26 and the aperture 4a in the vacuum pickup head 4.

The elevator block 26 is initially positioned below the table 18 so as to permit the forward edge of a label being fed thereto to clear the rear edge of the platform

26 and thereby prevent the possible buckling up of the label on the strip being fed thereto.

All of the above-described parts of the material handling device forward of the finger 20 have been positioned adjacent or below the surface of the table 18 so as to provide clearance for, and to avoid contact with, the pickup head 4 when it moves into position above the elevator block 26 and picks up a label from the block 26. Likewise as shown in FIG. 7, the elevator platform 26 is elevated above the surface of table 18 for pickup of a label by the pickup head 4 to further provide such clearance and avoid such contact. Otherwise, if the pickup head 4 had to be lowered to the level of the surface of table 18 such undesired contact could not be avoided.

The timed sequential movement of the various parts of the invention are controlled by a cam 54 on cam shaft 10. The cam 54 has a raised portion 54a and a depressed portion 54b. A cam actuated valve 55 is controlled by the cam 54. A control rod 56 extends from one end of the valve 55. The valve 55 is controlled by movement of the rod 56 therein. A lever 57 extends downwardly over the rod 56. The lever is pivoted about a pin 58 which is secured to an edge of the valve 55. As shown in FIG. 10, upon clockwise rotation of the cam 54, the raised portion 54a engages the lever 57 and moves it toward the valve 55. The lever 57 thereby depresses the control rod 56 into the valve 55 for control thereof.

FIG. 10 shows the pneumatic circuit controlled by the cam actuated valve 55. Valve 55 is a two-position spring return control valve and is shown in FIG. 10 in its initial position. From the source of air pressure P, air under pressure moves through lines 59 and 61 to maintain the piston in cylinder 41 in the right position shown. The movable cutter 25b and the elevator platform 26 are held in their initial lowered position by the piston rod 40. Also the piston rod 21 in cylinder 22 is holding the finger 20 in its forwardmost position with a label positioned on the elevator block 26. At this time the source of vacuum V is connected to the aperture 4a of pickup head 4 through valve 70. From this initial position of valve 55, one complete cycle of operation will now be described.

When the machine operator desires another label to be sewn, suitable mechanism effects a 360° rotation of the cam shaft 10 and cams 9 and 54. Upon rotation of cam 54 by cam shaft 10, raised portion 54a pivots lever 57 about pin 58 to depress control rod 56 into control valve 55. Upon depression of control rod 56, the air under pressure from source P is shifted from lines 59 through 63 to lines 65 through 69. Lines 59 through 63 are now connected to atmosphere through the valve 55. The air under pressure in line 67 moves through the adjustable restrictor 71a of the adjustable flow control valve with bypass 71 and moves the piston in cylinder 41 from right to left. As previously described, the piston rod 40 thereby moves the movable cutter 25a and elevator platform 26 upwardly. The adjustable restriction 71a controls the speed at which the piston and piston rod 40 moves and thereby controls the rate of ascent of movable cutter 25b and elevator platform 26.

The air forced from the left end of cylinder 41 moves through lines 61 and 59 through valve 55 to the atmosphere. Therefore, as no air under pressure enters lines 60, 62, 63, the piston in cylinder 22 remains in its initial right position.

Simultaneously with the movement of the piston in cylinder 41 from right to left, the air under pressure in lines 66 and 69 actuates the two-position spring return valve 70 to shift the source of vacuum V from the aperture 4a of the pickup head 4 to the aperture 26a of elevator block 26 through line 26b. By this vacuum the label is securely held on elevator block 26 during the cutting and elevating.

Simultaneously with the above-described movements cam 9 is likewise rotated and raised section 9a engages cam follower portion 11a to swing the vacuum head 4 outwardly from the sewing head 1 to a position above the elevator block 26.

Also simultaneously with the above-described movements, the air under pressure is moving from line 66 into line 68 through an adjustable restrictor 72a of an adjustable control valve with bypass 72. Restrictor 72a is adjusted so that just after elevator block 26 reaches its elevated position and just before the pickup head 4a moves to pickup the label from the elevator block 26, sufficient air under pressure has passed through restrictor 72a and into line 68, which together with the spring force of the return spring in valve 70, overcome the pressure exerted in line 69. Thereby the source of vacuum V is shifted from the line 26b back to the line 4b. Thereby the vacuum exerted through aperture 26b is cut off and releases the label and the vacuum exerted through aperture 4a of the pickup head 4 causes the label to be picked up by the pickup head 4 when it moves into position for such pickup.

The head 4 is lowered, picks up the label, and then raises. After pickup of the label by the head 4 and the raising thereof, the cam shaft 10 has rotated cam 9 so that the raised portion 9a has passed the cam follower portion 11a. The cam follower portion 11a then engages depressed section 9b of cam 9 and the pickup head 4 is swung inwardly to the sewing head 1 to a position adjacent the needle 3 for sewing the label onto a garment.

Likewise, after pickup of the label, the cam shaft 10 has rotated the cam 54 so that the raised portion 54a passes the lever 57 and releases it. Thereby the spring in valve 55 returns the control rod 56 to its initial position and the source of air under pressure P is shifted from lines 65 through 69 back into lines 59 through 63. Lines 65 through 69 are now connected to atmosphere through valve 55. The spring in valve 70 maintains the source of vacuum V to line 4b. The air under pressure shifts the piston in cylinder 41 from left to right. The piston rod 40 thereby moves the movable cutter 25a and elevator platform 26 back downwardly to their initial lowered position.

Simultaneously with the movement of the piston in cylinder 41 from left to right, the air under pressure in lines 60 and 63 actuates the two position spring return valve 64 to shift the source of air under pressure P from line 76 to line 74 to move the piston in cylinder 22 from left to right. Thereby piston rod 21 moves through its reverse stroke and moves finger 20 rearwardly to its rearward position. The air leaving the right end of cylinder 22 passes to the atmosphere through line 76.

Also simultaneously with the movement of the piston in cylinder 41 from left to right and the movement of the piston in cylinder 22 from left to right, the air under pressure is moving from line 60 into line 62 through an adjustable restrictor 73a of an adjustable control valve with bypass 73. Restrictor 73a is adjusted so that after the piston in cylinder 41 reaches its far right position

sufficient air under pressure has passed through restrictor 73a and into line 62, which together with the spring force of the return spring in valve 64, overcome the pressure exerted in line 63. Thereby, the source of air under pressure P is shifted from line 74 back to line 76. Thereby the piston rod 21 moves through its forward stroke and moves the finger 20 forwardly in a label-feeding direction to move another label onto elevator platform 26. The air leaving the left end of cylinder 22 passes to the atmosphere through line 74 and adjustable restrictor 75. The restrictor 75 controls the speed at which the piston rod 21 moves and thereby controls the speed of the finger 20 in its forward label-feeding movement. After the cam shaft 10 has rotated so that cam follower portion 11a engages depressed portion 9b of cam 9 and raised portion 54a has passed level 57, the cam shaft stops its rotation. The cam shaft 10 has thus completed 360° of rotation. One complete cycle has now been described.

When the operator desires another label to be sewn onto a garment the above-described cycle is repeated.

I claim:

1. A material handling device for use with a machine having a pickup head for moving pieces of material cut from a strip from one position to another position, said device comprising:

a substantially horizontally extending platform for supporting a portion of material, means for feeding a portion of a strip of material to said platform in a material-feeding direction, and a cutter intermediate said feeding means and said platform for cutting a portion of material from a strip of material whereby after a portion of material is cut from a strip of material that portion lies on the platform.

2. The material handling device of claim 1 further comprising:

a base having a substantially horizontally extending surface beneath the feeding means, the feeding means feeds the material along the surface to the platform, and the platform receives a portion of material from the feeding means and thereafter elevates the portion to a position above the surface to be picked up by a pickup.

3. The material handling device of claim 2 wherein: the cutter comprises a movable blade which extends transverse to the material-feeding direction and is initially positioned below the surface, and the movable blade moves upward to cut the portion as the platform elevates the portion.

4. The material handling device of claim 3 wherein: the platform is elevated in response to the upward movement of the movable blade.

5. The material handling device of claim 4 wherein: the movable blade is secured to a transversely extending arm of a crank arm, the other arm of the crank arm being connected to a means for actuating the movable blade, the movable blade being pivotable about a longitudinally extending axis defined by the point of intersection of the arms of the crank arm, and the bottom of the platform rests on the transversely extending arm so that when the movable blade is actuated by the actuating means, the transversely extending arm pivots about said axis and moves upward and simultaneously elevates the platform and moves the movable blade upward.

6. The material handling device of claim 2 wherein: the base has a longitudinally extending groove therein which extends below the surface, the feeding means comprises a reciprocable finger driven by a piston in a cylinder, 5 the finger has a tip which extends downwardly and in a material-feeding direction, and a portion of the tip extends into the groove, the strip of material is fed from a reel on which the strip has been wound, said strip having a plurality of spaced transversely extending slits therein, and the reciprocable finger has a stroke longer than the spacing between adjacent slits whereby on each material-feeding stroke of the finger the tip thereof engages one of the slits and advances the strip material a distance substantially equal to the spacing between adjacent slits.

7. The material handling device of claim 6 wherein: a pair of guide elements are positioned on said surface, 20 said elements being spaced apart a distance substantially equal to the width of the strip with the groove positioned centrally therebetween for guiding the strip along the surface as the strip is fed by said feeding means.

8. The material handling device of claim 2 wherein: the elevator platform is initially positioned below the surface.

9. The material handling device of claim 8 wherein: the cutter comprises a movable blade extending 30 transverse to the material-feeding direction and is initially positioned below the surface, said cutter also comprising a stationary blade positioned adjacent said surface and extending transverse to the material-feeding direction, 35 the stationary blade has a bevelled portion which faces downwardly and in a direction opposite to the material-feeding direction for guiding the portion of the strip from the surface downwardly to the initial position of the work station and for also positioning the strip between the stationary blade and movable blade for cutting the portion from the strip when said movable blade moves upward past said stationary blade.

10. The material handling device of claim 1 wherein: the platform comprises an upwardly facing surface having at least one aperture therein, and means connecting said at least one aperture to a 50 vacuum source whereby a portion of material lying on said surface will be held thereon by vacuum.

11. The material handling device of claim 10 herein: said surface is substantially level.

12. A machine comprising: a substantially horizontally extending platform for 55 supporting a portion of material, means for feeding a portion of a strip material to said platform in a material-feeding direction, a cutter intermediate said feeding means and said platform for cutting a portion of material from a strip of material whereby after a portion of material is cut from a strip of material that portion lies on the platform, and a pickup head for picking up a cut portion of material lying on said platform and for moving the cut portion from its position on the platform to another position on the machine.

13. The machine of claim 12 wherein:

10 said machine is a sewing machine having a sewing needle, and said pickup head picks up a cut portion of material from said platform and moves the cut portion from its position on the platform to another position on the sewing machine adjacent the needle.

14. The machine of claim 12 further comprising: a base having a substantially horizontally extending surface beneath the feeding means, the feeding means feeds the material along the surface to the platform, and the platform receives a portion of material from the feeding means and thereafter elevates the portion to an elevated position above the surface to be picked up by the pickup head.

15. The machine of claim 14 wherein: the cutter is below the platform in its elevated position so as not to contact the pickup head when it picks up the cut portion lying on the platform.

16. The machine of claim 14 wherein: the cutter comprises an upwardly movable blade which is initially positioned below the surface, and the platform is elevated in response to the upward movement of the movable blade.

17. The machine of claim 14 wherein: the cutter comprises a movable blade which is initially positioned below the surface, and said cutter also comprises a stationary blade positioned adjacent said surface.

18. The machine of claim 17 wherein: the elevator platform is initially positioned below the surface.

19. The machine of claim 18 wherein: the stationary blade has a bevelled portion which faces downwardly and in a direction opposite to the material-feeding direction for guiding the portion of the strip from the surface downwardly to the initial position of the platform.

20. The machine of claim 12 wherein: the platform comprises an upwardly facing surface having at least one aperture therein, and means connecting said at least one aperture to a vacuum source whereby a portion of material lying on said surface will be held thereon by vacuum.

21. The machine of claim 20 further including: valve means for disconnecting said at least one aperture from said vacuum source as said pickup head moves to pickup the cut portion from the platform.

22. The machine of claim 21 further including: means connecting a portion of the pickup head to a vacuum source whereby the cut portion is picked up by said pickup head from said platform by vacuum.

23. The machine of claim 22 wherein: the valve means switches the vacuum source from said at least one aperture on the platform to the portion of the pickup head as said pickup head moves to pick up the cut portion from the platform.

24. The machine of claim 12 wherein: the platform comprises an unobstructed upwardly facing surface so as not to contact the pickup head when it picks up the cut portion from the platform.

25. The machine of claim 24 wherein: the surface is substantially level.

26. A material handling method comprising the steps of: supporting a portion of a strip of material,

11

cutting the portion from the remainder of the strip of material,
 elevating the cut portion,
 picking up the elevated cut portion,
 and thereafter feeding a portion of the remainder of the strip of material for subsequent supporting, cutting, and elevating thereof.

27. The method of claim **26** wherein:
 the steps of cutting and elevating occur substantially simultaneously.

28. A material handling method comprising the steps of:

12

feeding a portion of a strip of material, supporting the portion of the strip of material, cutting the portion from the remainder of the strip of material, and elevating the cut portion.

29. The method of claim **28** wherein:
 the steps of cutting and elevating occur substantially simultaneously.

30. The method of claim **29** further comprising:
 picking up of the elevated cut portion.
